UNITED STATES PATENT OFFICE.

JENNIE A. HOYT, OF LOS ANGELES, CALIFORNIA, ASSIGNOR TO SCOTT E. ALLEN, HAL D. RIVES, AND FRANK CARROLL, ALL OF LOS ANGELES, CALIFORNIA.

SWING-SPOUT MEASURING-CAN.

1,330,537.

Specification of Letters Patent. Patented Feb. 10, 1920.

Application filed February 8, 1919. Serial No. 275,907.

To all whom it may concern:

Be it known that I, JENNIE A. HOYT, a citizen of the United States, residing at Los Angeles, in the county of Los Angeles and State of California, have invented a new and useful Swing-Spout Measuring-Can, of which the following is a specification.

My invention relates to measuring cans such as are used for measuring liquids, being more particularly a measuring can to be used for measuring oils and similar substances. My invention is designed particularly to be used in placing oils in the engines of automobiles, the usual procedure in so doing being to fill the measure from the receptacle holding the oil, after which the oil is carried to the automobile and the contents of the can poured into the crank case. Ordinarily such cans are filled to the very top and any slight jar or unsteadiness in carrying the can causes the oil to slop over the sides of the can and drip.

As these cans are used at filling stations for dispensing oil to the public in some communities ordinances or statutes provide that such cans shall have a single filling line. To comply with this requirement and to provide a can from which the oil cannot be easily slopped in carrying the same, I have devised a can having an inwardly curved upper rim, preferably half round in cross-section, the inner edge of the rim being below the top of the can and constituting the filling line.

The principal object of my invention is to provide a measuring can of simple form and construction having a swing spout and so constructed at its upper portion that the contents of the can are not easily spilled therefrom.

Referring to the drawings, which are for illustrative purposes only,

Figure 1 is a side elevation partly in section showing a can embodying a form of my invention.

Fig. 2 is a vertical sectional view on line 2-2, Fig. 1, the spout being turned into discharging position.

Fig. 3 is a plan view of the can shown in Fig. 1.

The can or measure 11 is provided with a handle 12, the lower portion of the can terminating in a foot rim 13 provided in its forward portion with an opening 14 be-

low the bottom 15 of the can. 16 designates a spout having a horizontally extending portion 17 and a vertical portion 18 which extends upwardly in front of the can and terminates at its upper end in an outwardly extending portion 19.

The spout 16 is soldered or mounted at its lower end upon a spout sleeve 20 mounted upon a tube 21, the sleeve 20 and tube 21 being slightly tapered and a coiled spring 22 serving to keep the tube sleeve in close contact with the tube 21. The tube 21 is provided with an opening 23 arranged to deliver the contents of the can through the spout when the spout is in the dotted line position shown in Fig. 1. The tube 21 is in open communication at one end with an opening or discharge outlet 24 formed in the bottom of the can so that all of the contents of the can are drained into the spout when the spout is in the dotted line position shown in Fig. 1. When the spout is in the full line position shown in Fig. 1 the opening 23 is closed to prevent the flow of liquid into the spout.

The upper portion of the can terminates in an inwardly extending rim 25, in the form shown, being made of a separate piece of metal secured by solder or in any suitable manner to the open upper end 26 of the can. The rim 25 is preferably half round in cross-section as shown in Fig. 1, the inner edge 27 being substantially on a line with the top edge 26 of the can and forming or constituting the filling line. For example, assuming the measure shown to be a quart measure, when the spout is in full line position shown in Fig. 1 and the measure filled to the edge 27 as indicated, the measure contains one quart.

The can is used in the following manner:

When the can has been filled as above described as is ordinarily done in a filling station, the can is carried to the automobile with the spout in the full line position shown in Fig. 1. During this carrying operation should the can be held in an uneven position or jarred the oil may slop into the space or chamber 28 within the rim 25, or should the oil come up on the rim it has the height of the rim from the edge 27 to flow before any of the oil is spilled from the can. When the can is emptied into the automobile it is understood that the spout

is moved downwardly into the dotted line position shown in Fig. 1 when the contents of the can are discharged through the spout.

What I claim is:—

- 5 1. A measuring can comprising a measure, means whereby liquid may be drawn from the can when in upright position, and an inwardly extending rim formed on the upper end of the measure, the inner edge of
- 10 said rim constituting the filling line of the can and being parallel with the bottom of the can.

2. A measuring can comprising a measure, means whereby liquid may be drawn from the can when in upright position, a half 15 round rim formed on the upper end of said measure, said rim terminating in a downwardly extending edge forming the filling line of said measure.

In testimony whereof I have hereunto set 20 my hand at Los Angeles, California, this 30th day of January, 1919.

JENNIE A. HOYT.
